UNITED STATES PATENT OFFICE.

JOHN M. HANSEN, OF CLEVELAND, OHIO.

DESIGN FOR A COMBINED LAMP AND CLOCK STAND.

57,226.

Specification for Design.

Patented Mar. 8, 1921.

Application filed March 5, 1920. Serial No. 363,564. Term of patent 14 years.

To all whom it may concern:

Be it known that I, JOHN M. HANSEN, a citizen of the United States, residing at Cleveland, in the county of Cuyahoga and State of Ohio, have invented a new, original, and ornamental Design for Combined Lamp and Clock Stands, of which the following is a specification, reference being had to the accompanying drawing, forming a part thereof.

The figure is a perspective view of a combined lamp and clock stand showing my new design.

I claim:

The ornamental design for a combined lamp and clock stand as shown.

JOHN M. HANSEN.
